(No Model.)

C. VAN DUSEN.

AUTOMATIC CAR BRAKE.

No. 284,690.

Patented Sept. 11, 1883.

INVENTOR,
Charles Van Dusen
by Wm. Finchel
Attorney

UNITED STATES PATENT OFFICE.

CHARLES VAN DUSEN, OF NEW ALBANY, INDIANA, ASSIGNOR OF ONE-HALF
TO WILLIAM L. BREYFOGLE, OF LOUISVILLE, KENTUCKY.

AUTOMATIC CAR-BRAKE.

SPECIFICATION forming part of Letters Patent No. 284,690, dated September 11, 1883.

Application filed June 30, 1883. (No model.)

To all whom it may concern:

Be it known that I, CHARLES VAN DUSEN, a citizen of the United States, residing at New Albany, in the county of Floyd and State of Indiana, have invented certain new and useful 5 Improvements in Automatic Car-Brakes, of which the following is a full, clear, and exact description.

This invention is in the nature of improvements 10 on the car-brake for which Letters Patent of the United States No. 269,142 were granted to me, December 12, 1882, and the objects of the improvements are to simplify 15 the brake-setting mechanism operable by the buffers, and to provide in this class of brakes an improved brake-setting mechanism operable upon the parting of any two of the cars in a train.

With these objects in view the invention 20 consists in the combination and arrangement of parts hereinafter specifically set forth and claimed.

In the accompanying drawings, in the several figures of which like parts are similarly 25 designated, Figure 1 is a longitudinal central section of the ends of a railroad-car containing my improvements, the left-hand or bottom end of said figure showing the buffer-operated 30 brake-setting mechanism only, and the right-hand or upper showing the mechanism for setting the brakes by the uncoupling of the cars. Fig. 2 is a cross-section of the draft-timbers of the car on the line $x-x$ of Fig. 1, showing a modification. Fig. 3 is a top plan view of the 35 automatic coupling devices for setting the brakes upon the accidental parting of the train. Fig. 4 is a side elevation on one member of said device. Fig. 5 is a rear end view of a slight modification of my buffer-bar as applied 40 to certain kinds of tenders, and Fig. 6 represents in side elevation and bottom plan view the details of a preferred form of buffer.

The body, bottom, draft-timbers, and trucks 45 of a railway-car may be and are here shown of ordinary construction to receive my invention. Suitably supported in the sills or other frame-work of the car, about centrally thereof, and preferably above the draw-heads, is a rod or bar, a , extending the length of the car and 50 projecting beyond the platforms at both ends.

Upon the ends of this bar are secured buffers b , of ordinary or preferred construction. In Fig. 6 I have shown a buffer with a flat contact-face, b' , and in a recess beneath said face I have arranged a fork, b'' , for use in holding 55 the coupling-pin. The rod or bar a is provided with a toothed rack, c , and between said rack and a stationary part of the framing is a spring, d , tending to keep said bar projected. A toothed wheel, e , meshing with the rack of 60 the bar a , is mounted upon a shaft, f , having bearings in and transversely of the draft-timbers g , and a second and smaller gear-wheel, h , is mounted upon a shaft, i , also borne by said draft-timbers, said gear-wheel h meshing 65 with the wheel e , and being driven thereby. The end of the shaft i has arms j , to which branches k of the brake-chain l are secured. The brake-chain l is connected in any usual 70 or suitable manner with the brake-shoe-operating mechanism. If it be desired to rotate the shaft i more rapidly than motion can be obtained from a train of two gear-wheels, I may place on the shaft f another and larger gear-wheel, e' , and set the gear-wheel h to one 75 side of the wheel e to mesh with said wheel e' , substantially as shown in Fig. 2.

The tender will be provided with a brake-setting mechanism of substantially the character just described, which mechanism will be under the control of the engineer, and may consist of a steam-operated piston moving a series 80 of levers or chains and pulleys arranged in any obvious manner, to bear upon the buffer b and press it toward the rear of the tender, 85 whereby its rear buffer, borne by the bar a , will bear upon the front buffer of the first car, and retracting it will set in operation, through its toothed rack-bar a , the train of gearing on that car and set its brakes, and as the bar a of that car is continuous of the car, and has 90 its rear end projecting beyond the rear end of the rear platform, the buffer on that end will bear upon the front buffer of the next car and set its brakes by a similar mechanism, and so 95 on throughout the whole train. By dividing the brake-chain into two branches connected to arms of the shaft i of the operating-gearing, as shown, the brake mechanism is operable from either end of the car. When the pressure 100

upon the tender-buffer is removed, the springs *d* are free to operate, and by throwing out the rod or bar *a* bring its buffers into normal position and release the brakes.

5 The buffer provided with the fork for holding the coupling-pin is an essential element in my brake mechanism when the rod *a* and draw-head are so close as to prevent the pin being set in the hole therein, as usual. It will be remembered that ordinarily the pin is set in the hole and leans back toward the car, so that as the cars come together the entrance of the link into the draw-head and the concussion will serve to cause the pin to drop and engage 15 the link. Now, where my buffer and rod extend over the draw-head, as indicated in the drawings, and thus they usually will, the coupling-pin hole is covered, and the pin hence could not be placed therein, so that it becomes 20 necessary to employ a device such as I have shown in order to ready placing in of the pin. It could not lean against the buffer, and so must be held by it.

By my construction I dispense with couplings for the series of brake-operating mechanisms in the cars composing a train, and yet make them mutually dependent for operation. The ordinary hand-operated mechanism for the brakes may be retained as an auxiliary to my 30 automatically-operated mechanism.

Where the construction of the rear end of the tender is such as to preclude the running the bar *a* straight through, it may be forked, as at *a' a'*, Fig. 5, to encompass such obstruction, 35 and the buffer supported on said forked end by legs connected therewith, substantially as illustrated in said Fig. 5.

I have herein shown as a useful but not necessary adjunct to this form of brake-setting mechanism improved means for setting the brakes upon the accidental uncoupling or parting of the cars of a train, which I will now proceed to describe.

m is a segmental lever, having its fulcrum 45 *n* fast between or on the draft-timbers, and arranged at each end of each car of a train, and, if desired, upon the tender. One end of this lever has a link, *o*, engaging in any suitable manner the buffer-bar *a*. The other end 50 of this lever has pivoted to it a bar, *p*, terminating in a hook, *q*, and said bar may be suspended from the platform loosely by a chain, *r*. A guard, *s*, mounted upon the hook *q* to cover and uncover the entrance thereto, is connected to rod *t*, with a spring, *u*, fixed at one end to said rod, and bearing against an ear on the guard to keep said guard normally over 55 the mouth of the hook *q*. The rod *t* is suitably guided upon the bar *p*, and may be made as a 60 crank at its rear, and has a bearing, *v*, in the lever *m* at a point nearer the fulcrum of said lever than the pivot of the bar *p*. These hooks and their guards will be in reverse position on the opposite ends of each car, so that 65 the hooks of meeting ends of adjacent cars will be in position to engage each other. As

the cars are coupled the hooks *q* of adjacent cars will strike the guards *s*, and as said guards move loosely and freely upon their rods *t* said guards will be so moved by the approaching 70 hooks as to clear the mouths of said hooks, and when said hooks have been so engaged the guards *s* are free to be moved by their springs into their normal position over the mouths of said hooks, whereby the engaged 75 hooks will be locked or retained in their engagement. In this position of the hooks, should the cars begin to separate, the strain upon the bar *p* acts upon the lower ends of the levers *m*, drawing them toward the adjacent 80 ends of their respective cars and causing the movement of the upper ends of said levers in the opposite direction, whereby the links or chains *o* are made to act upon the buffer-rods *a*, moving them so as to cause their toothed 85 racks to engage the trains of gearing and set the brakes of the adjacent cars. This motion of the buffer-rods is communicated to the buffer-rods of the other cars to an extent sufficient to give the engineer notice of 90 the trouble. A gravity-pawl, *w*, engages notches *y* on the lever *m* to hold said lever in any position to which it may be brought by the pull of the bar *p*; hence the pawls throughout the train will hold the brakes, when once 95 set, until positively released. As the levers *m* are moved the difference in the radii of the pivotal points of the bars *p* and rods *t* will cause a gradual retraction of the rods *t*, and consequently the movement of the guards *s*, 100 until said guards uncover the hooks and permit them to drop apart; but this can only occur when the brakes are fully set up.

I have thus greatly simplified the construction of this class of car-brakes, dispensed with 105 much costly gearing, and rendered the brake direct acting.

I have confined my illustrations and description herein to a single form for convenience merely; but it will be understood that 110 many parts may be altered in shape and form so long as their respective functions, herein stated, are preserved.

What I claim is—

1. In an automatic car-brake, a buffer-rod 115 extending continuously from one end of the car to the other, and supplied with buffers at each end, combined with a toothed rack, a train of two or more gear-wheels, a double-arm shaft driven by said gear-wheels, and a brake-chain 120 having branches connected separately to the arms of the said double-arm shaft, substantially as shown and described.

2. The combination, substantially as shown and described, in an automatic brake, of a 125 movable rack-bar extending from end to end of the car, and provided with buffers at each end, springs to hold said bar normally projected, a shaft having two arms extending in different directions therefrom, gearing connecting said shaft and the rack-bar, and a 130 brake-chain connected to each of said arms,

whereby the brakes are set when the buffer rack-bar is moved from either end of the car, as set forth.

3. The combination, substantially as shown 5 and described, with an automatic-brake-setting mechanism comprising a buffer rack-bar extending from end to end of the car, a shaft having two arms extending in different directions therefrom, a brake-chain connected to 10 said arms by branches from its body, and gearing between said shaft and the rack-bar, of a segmental lever connected loosely with but engaging said buffer-bar, and provided with a hook having a spring-guard independently 15 connected with said lever, to hold the hooks of adjacent cars in contact, and to operate said lever upon the pulling apart of uncoupled cars to set the brakes, and then disengage the hooks, as set forth.

4. The combination, substantially as shown 20 and described, of a segmental lever, *m*, link *o*, buffer-bar *a*, bar *p*, hook *q*, guard *s*, spring *u*, rod *t*, and pawl or detent *w*, as and for the purpose described.

5. The combination, with the projecting 25 movable rod *a*, of the buffer *b*, shaped substantially as shown and described, and provided with the fork *b*, for holding the coupling-pin, as set forth.

In testimony whereof I have hereunto set 30 my hand this 25th day of June A. D. 1883.

CHARLES VAN DUSEN.

Witnesses:

W. H. BERKELE,
JNO. K. FAULKNER, Jr.

It is hereby certified that in Letters Patent No. 284,690, granted September 11, 1883, upon the application of Charles Van Dusen, of New Albany, Indiana, for an improvement in "Automatic Car-Brakes," errors appear in the printed specification requiring correction, as follows: In line 37, page 1, the word "on" should read *of*; at end of line 71, page 2, after the word "hooks," the words *and permit the engagement of the hooks* should be inserted; and that the patent should be read with these corrections therein to make it conform to the record of the case in the Patent Office.

Signed, countersigned, and sealed this 18th day of September, A. D. 1883.

[SEAL.]

M. L. JOSLYN,
Acting Secretary of the Interior.
